CLAIM

The ornamental design for a square furniture pull knob, as shown and described.

DESCRIPTION

FIG. 1 is a perspective view looking from the bottom of a square furniture pull knob showing my new design;

FIG. 2. is a top plan view thereof;

FIG. 3 is a bottom plan view thereof, the broken line portion thereof forms no part of the claimed design; and,

FIG. 4 is a first side elevational view thereof, the other 3 sides being identical thereto.
